UNITED STATES PATENT OFFICE.

CLARK F. RIGBY, OF BUTLER, PENNSYLVANIA.

SUCKER-ROD JOINT.

1,250,509.

Specification of Letters Patent.

Patented Dec. 18, 1917.

Application filed April 11, 1916. Serial No. 90,369.

To all whom it may concern:

Be it known that I, CLARK F. RIGBY, a citizen of the United States, and resident of Butler, in the county of Butler and State of Pennsylvania, have invented certain new and useful Improvements in Sucker-Rod Joints, of which the following is a specification.

The primary object of the present invention is to provide an efficient substitute for the wood sucker rods commonly employed in the pumping of oil wells, the scarcity and high cost of wood suitable for the purpose rendering this feature of oil well equipment a very material item.

A further purpose is to provide an improved coupling for the sucker rod sections quite irrespective of the material of which the sections are formed, a coupling not dependent on a screw connection as heretofore but one made operative by relative lateral movement of the coupling parts when out of the well tubing, the latter precluding disconnection when the coupled rod sections are operating therein.

Another purpose is to provide a swivel-forming coupling whereby the rod sections may rotate relatively to each other without impairing the connections and avoiding the not infrequent disconnections incident to the screw connected sections of rods now generally in use.

In the accompanying drawings, Figure 1 is an elevation of sucker rods and coupling means embodying the invention, the parts being shown in position in a well tube. Fig. 2 is a vertical longitudinal section at right angles to Fig. 1, being taken on line 2-2 of Fig. 1. Fig. 3 is a cross-section on line 3-3 of Fig. 1.

Referring to the drawings, 2 designates the sucker rod sections which in the present embodiment are formed of metallic tubing, the sections being adapted to be united by coupling heads 3 and 4. The cross-sectional area of the heads is such as to afford them a working fit in well tubing A, the arrangement being such as to preclude relative lateral uncoupling movement of the heads when in use. The heads are preferably of the general angular form as shown in Fig. 3, the corner-like ribs 5 having the clearance fit within tubing A above referred to and with the extremities of said ribs beveled at 5' to avoid obstructing engagement with extremities A' of the tubing within the cou-

pling sockets B. The exterior of each of heads 3 and 4 between ribs 5 is grooved or indented from end to end of the head as indicated at 6 to provide channels for the unobstructed flow of fluid.

The distant extremity of each of heads 3 and 4 is formed with a pin-like projection 7 which is entered in the extremity of the tubular rod 2, shoulder 7' on the pin producing a corresponding off-set 2' in tube 2 when the parts are united to provide a secure union. In forming this union it will be understood that the extremity of tubing 2 is conformed to the shape of pin 7 while heated, or pin 7 as well as the tubing may be heated for providing a welded joint.

Coupling head 3 is recessed upwardly from its lower end at 8, the upper portion of the recess being enlarged above the upwardly facing shoulder 8'. Recess 8 is open laterally through one side of the head as indicated at 9. Projecting from coupling head 4 is the shouldered extension 10 which is adapted to be entered through the open side 9 of cavity 8 by relative lateral movement of heads 3 and 4 when out of tubing A. With the heads coupled together as in Figs. 1 and 2 they have a working fit in tubing A, but disconnecting or uncoupling lateral movement is impossible. With the annular shoulder 10' of extension 10 bearing on the corresponding shoulder 8' of cavity 8, a swivel connection is formed whereby the sections may turn relatively to each other with no uncoupling tendency as is the case with screw connected sections heretofore employed.

For opposing disconnecting movements of the coupling heads when the rods are out of the well tubing so that they will ordinarily remain united until some effort is made to separate them, a vertically movable latch pin 11 is normally slightly projected from the upper extremity extension 10 and is adapted to enter rounded depression 12 on the top face of cavity 8. With the extremity of latch 11 rounded, it will be automatically depressed by the coupling and uncoupling movements of the heads, yet will offer sufficient resistance to appreciably oppose separation in the absence of effort exerted to accomplish that purpose. Latch 11 is shouldered at 11' and confined within cavity 12 by bushing 13, the spring 14 within the cavity holding the latch normally projected against the bushing.

The invention herein utilizes metallic rods which are strong and less expensive than the wooden rods ordinarily used. In addition, the simple and efficient coupling provides a 5 swivel connection which cannot be uncoupled so long as the parts are within the well tubing.

I claim:

1. In combination, sucker rod sections 10 provided with coupling heads, each head having exterior longitudinal fluid passages within the well tubing, each head being also exteriorly formed to engage the interior surface of the well tubing and thereby maintain the approximate longitudinal alinement 15 of said heads, one head being formed with a longitudinal socket opening through its end and side and the other head having a complementary portion adapted to enter said socket by relative lateral movements of the heads at the exterior of the well tubing, said heads providing corresponding transverse abutments to sustain end thrust and to maintain the heads against approximate 20 independent longitudinal movement, said socket and complementary portion being relatively formed to provide for relative rotary movement of either head with respect to the other when coupled together.
2. In combination, sucker rod sections 25 provided with a pair of co-operating coupling heads, one of said heads having a socket opening through the end and a side of the head and contracted intermediate its length, the longitudinal axis of said socket being approximately alined with the longitudinal axis of the head and having its interior surfaces approximately concentric with said axis, the other head having a complementary 30 reduced portion the longitudinal axis of which is approximately alined with the longitudinal axis of the head and having its exterior surface approximately concentric with said axis, said heads having abutting 35 transverse shoulders to resist independent longitudinal movement in either direction when assembled, substantially as described.
3. In combination, sucker rod sections 40 provided with enlarged laterally-separable coupling heads fixed and in continuation of the ends of said sections, the meeting ends of said rods formed to laterally interlock against material longitudinal movement in 45 either direction and to permit lateral separation when removed from the tubing, each head having beveled-end longitudinal radially projecting spaced wings to engage the well tubing with a working fit to maintain said heads longitudinally alined and to prevent swaying of the rod and to provide exterior intervening longitudinal liquid passages, substantially as described.
4. In combination, sucker rod sections 50 provided with coupling heads, one of said heads having a socket with its longitudinal axis approximately alined with the longitudinal axis of the head and laterally opening through a side thereof and longitudinally opening through the end of the head, the other head having a complementary portion laterally movable to and from said socket and interlocking therewith to normally maintain said heads in longitudinal alinement and against substantial independent longitudinal movement in either direction, the longitudinal axis of said complementary portion being approximately alined with the longitudinal axis of its head, the interior and exterior surfaces of said socket 55 and portion being formed to permit independent rotation of said heads on their common longitudinal axis, one of said heads provided with a longitudinally-yielding catch pin alined with said axis of independent rotation, the other head having a socket normally receiving said pin and alined with the longitudinal axis thereof.
5. In combination, sucker rod sections 60 provided with coupling heads, one of said heads having a longitudinal central socket opening through the outer end thereof and having an internal intermediate shoulder, said socket throughout its length opening through a side of the head and having a central depression in its inner end wall, the other head having a complementary central longitudinal extension formed to laterally enter said socket and having approximately cylindrical surfaces and an intermediate 65 annular shoulder, said extension having a central longitudinal yielding catch pin projecting from its end and adapted to enter said depression.

In testimony whereof, I affix my signature in presence of two witnesses.

CLARK F. RIGBY.
